Des. 221,084
Patented July 6, 1971

221,084

ELECTRONIC IMPACT DATA PRINTER

Gregory F. Fossella, Marshfield, Mass., assignor to Nortec
Computer Devices, Inc., Ashland, Mass.

Filed Nov. 26, 1969, Ser. No. 20,287

Term of patent 14 years

Int. Cl. D14—02

U.S. Cl. D26—5

FIG. 1.

FIG. 2.

FIG. 3.

FIG. 1 is an axonometric view of an electronic impact data printer showing my new design;

FIG. 2 is a reversed axonometric view of the printer of FIG. 1, and

FIG. 3 is a top view of the printer of FIGS. 1 and 2.
I claim:

The ornamental design for an electronic impact data printer, substantially as shown.
